UNITED STATES PATENT OFFICE

JEAN DELATTRE-SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR TREATING HYDROCARBON OIL

Application filed January 28, 1925. Serial No. 5,337.

My invention relates to a process of cracking hydrocarbon oils, and more particularly to a process carried out in a tube and drum type of apparatus.

In the cracking of oil in the tube and drum type of apparatus there has been considerable difficulty experienced because of the formation and deposition of carbon in the heating tube or coil. There has also been a tendency to create too large a percentage of fixed gases and to generally produce an objectionable quantity of carbon even in the reaction drum when obtaining a high yield of light distillate. It is the object of my invention to provide a process in which I am enabled to prevent over-cracking of the less refractory constituents of the oil; to provide a process wherein carbon formation and deposition in the heating coil is substantially eliminated, as well as a process wherein the total quantity of carbon formed and fixed gases produced are materially lessened.

More specifically, my invention contemplates the superheating of a portion of the generated vapors and the return of such superheated generated vapors into the body of liquid oil in the reaction drum to maintain such body of oil at the optimum cracking temperature, to agitate this oil and to cause a re-combining of the superheated vaporous fractions with the liquid constituents of the oil to materially increase the reaction and the yield of light distillate and in general to provide a process and apparatus for the economic conversion of heavier into lighter hydrocarbons.

For the purpose of clearness and conciseness I will describe my process in connection with the apparatus disclosed in the accompanying drawings, wherein:

Figure 1 is a side elevation, partly in section, of an apparatus suitable for carrying out my process.

Fig. 2 is a detailed plan view of the carbon separator interposed in the superheated vapor line.

In carrying out the process, raw oil from any suitable source of supply (not shown) is drawn through the line 1 and forced by the pump 2 through the line 3 to the heating coil

7 or by proper regulation of the valves 5 and 6 the raw oil may be directed entirely through the line 4 to the top of the dephlegmator, or the stream of raw oil may be divided, a portion thereof passing directly through the line 3 to the inlet of the heating coil, while the remaining portion is directed through the line 4 to the top of the dephlegmator 18. The oil passing through the coil 7 disposed in the furnace 8 heated by the burner 9, is raised to a high temperature. The heated oil constituents are directed from the coil 7 through the transfer line 13 controlled by suitable throttle valve 14 to the enlarged reaction drum 15, wherein conversion takes place. A portion of the evolved vapors passes from the reaction drum 15 through the vapor line 16 controlled by valve 17 into the dephlegmating column 18. In this dephlegmator the heavier fractions of the vapors are condensed, forming reflux condensate, which is returned through the reflux leg 19 by means of the pump 21 to the raw oil charging line or it may be passed by gravity through the by-pass line 22 by suitably regulating valves 20, 23 and 24. The uncondensed vapors pass from the dephlegmator 18 through the line 25 in which is interposed a suitable, throttle valve 25^a to the final condenser 26 positioned in a condenser box 27. The pressure distillate and uncondensable gas pass from the condenser 26 through the line 28 controlled by valve 29 to the receiver 30. The receiver 30 is provided with liquid draw-off line 31 controlled by valve 32 and with uncondensable gas relief pipe 33 controlled by valve 34, it being, of course, understood that the receiver is provided with suitable liquid level and pressure gauges.

As a further feature of the invention the pressure distillate may be drawn off through the line 35 controlled by valve 36 and forced by the pump 37 through the line 38 to the dephlegmator 18 to act as a dephlegmating and stabilizing medium for the generated vapors.

The feature of my invention that I regard as most important comprises the withdrawal of a portion of the vapors from the reaction

drum 15, the superheating of these vapors and their return to the liquid body of oil in the reaction drum 15. To accomplish this I provide a vapor draw-off line 39 which communicates with the vapor space of the reaction drum 15 and is controlled by a suitable valve 40. This line 39 communicates with a pump or blower 41 which in turn connects to a coil 42 disposed in the upper portion 10 of the furnace 8 in the path of the escaping combustion gases from the furnace. A burner 11 is provided for applying additional heat to this coil 42 in the event it is found to be necessary. The vapors after passing through the coil 42 are directed to a header A. This header A communicates through lines B with carbon separators C, shown more particularly in Fig. 2. By suitable regulation of the various valves b the superheated vapors can be passed to any one of the carbon separators C interposed in the respective lines B. Provision is made for directing the vapors to these alternate carbon separators so that in the event that one of the carbon separators becomes charged with carbon it can be cut out of the system and the run continued by merely cutting in another of the carbon separators, it being understood that the charged separator can be cleaned while it is cut out of the system. These carbon separators do not specifically form any feature of my invention and are shown merely diagrammatically. They may, however, be provided with a screen such as shown at c. From the carbon separator through which the vapors are being passed they are directed to the common line 43 controlled by valve 44 and thence to the perforated spray member 45 disposed in the reaction drum 15 well below the normal liquid level therein. It will be readily apparent that by this means a portion of the generated vapors can be withdrawn from the reaction drum 15, superheated, and returned free of carbon to the liquid body of oil in said drum. The drum 15 is provided with vertically disposed residuum draw-off lines 46 controlled by suitable throttle valves 47. It will, of course, be understood that the carbon separators C can be readily dispensed with. The amount of carbon formed in the superheating of the vapors depends on the characteristics of the latter and on the degree of superheat given them. Due to the velocity and turbulence of the vapors passing through the superheating coil 42, through the line 43 and spray 45, the fine carbon particles are held in suspension and given no opportunity to adhere to the walls of the tube and will be to a considerable extent carried back into the reaction drum 15. The particular conditions which will be maintained in the various parts of the apparatus, for example, the coil 7, the drum 15, and the coil 42, and also the proportion of the vapors superheated and re-injected into the reaction drum, will vary depending on the

character and nature of the oil being treated.

The nature and character of my process can perhaps be best understood by comparing it with a process in which no portion of the vapors is passed through the liquid oil in the reaction drum. The following is an example of such a run carried out in my apparatus. A midcontinent fuel oil having a Baumé gravity of 25.1° was subjected in the heating coil to a temperature of substantially 880° F., while the temperature in the reaction drum averaged substantially 860° F. The vapors leaving the reaction drum to enter the dephlegmator were at a temperature of substantially 850° F. This run was carried out under a pressure of about 150 pounds. Under this process 40% of the charge was converted into gasoline having an end point of 437° F., 25% of the charge was converted into gas oil, while the residuum produced represented 29.5%. The uncondensable gas and dry coke amounted to 5.5% of the oil charged. For the purposes of comparison the following run is given, in which a portion of the vapors was withdrawn from the reaction drum 15, superheated, and returned to the liquid body of oil therein. In this run the same character oil was treated. The temperature to which the oil was subjected in the coil was substantially 730° F. The vapors which were superheated and returned to the drum were raised to a temperature of substantially 1100° F. These vapors were in the proportion of about 20% of the amount of the oil passed through the coil by weight. The average temperature maintained in the reaction drum was substantially 850° F. while the vapors leaving the chamber to be directed either into the dephlegmator or into the vapor heating coil were at a temperature of substantially 840° F. In carrying out this last-mentioned run 47% of the oil charge was converted into gasoline, having substantially the same characteristics as that produced in the preceding run, 23% of gas oil was produced, the residuum representing 28.7%, while the loss in dry carbon and uncondensable gas was reduced to 1.3%. The production of dry carbon when a portion of the vapors was withdrawn from the reaction drum, superheated and returned to that drum, was about one-half as much as was produced when no vapors were so superheated and returned. In the second run the fuel consumption was reduced about one-third.

I do not fully appreciate all of the reasons for the advantages obtained when a portion of the vapors is superheated and returned to the liquid oil in the reaction drum. I do, however, know that this operation when carried out as described gives the improved results.

It is my belief, however, that these advan-

tages can be explained in part by the law of mass action. The subjection of a portion of the vapors to the superheat action in the coil 42 has a tendency to additionally crack these vapors and to produce therefrom lighter or uncondensable gases and heavier portions or coke, which are normally end products formed in the main cracking zone. The injection of the latter into the reaction drum during the run will, according to the above law, greatly lessen the formation of further gas and coke to such an extent as to more than balance the quantities produced by the additional cracking of the vapors.

Furthermore, I believe that while it is true that some gases are formed in the passage of the vapors through the coil 42, these gases re-combine with fractions of the liquid constituents of the oil in the reaction drum 15 and result in the conversion of a greater percentage of the oil into light condensable fractions than can be obtained when no vapors and gases are returned to the oil body. The passing of the hot vapors and gases through the liquid oil in the reaction drum 15 makes it possible to maintain the oil therein at the optimum cracking temperature without necessitating the application of such a high heat to the oil in the coil 7 as to cause over-cracking of the less refractory constituents and formation of carbon therein.

Furthermore, this injection of the heated vapors into the liquid oil body keeps the oil in an agitated turbulent condition, maintains the carbon in suspension, and permits its withdrawal from the reaction drum with the residuum. It is well recognized in oil treatment that agitation of the oil by vapors or gas permits vaporization of substantial portions of the oil at lower temperatures. In my process, I employ this phenomena to increase vaporization in the reaction drum without the necessity of heating the oil in the coil to such a high temperature as will cause coking of the tubes. My experience has also shown that the conversion of the oil in the reaction drum is increased and accelerated by injecting heated vapors taken from the system into the oil in the reaction drum.

I claim as my invention:

1. A process for cracking hydrocarbon oil, consisting in continuously passing a stream of oil through an elongated passageway located in a furnace wherein the oil is highly heated, in transferring the highly heated oil from said elongated passageway into an enlarged reaction drum wherein a body of oil accumulates and conversion occurs, in passing evolved vapors from said drum to a dephlegmator, in condensing the dephlegmated vapors and collecting the resulting distillate, in augmenting the conversion of the oil in

said drum by withdrawing a portion of the hot vapors from the system, superheating such withdrawn vapors and injecting them into the liquid body of oil in said drum, and in maintaining a superatmospheric pressure on the oil undergoing conversion.

2. In an apparatus for treating hydrocarbon oil, a coil disposed within a furnace through which oil is adapted to be passed, a transfer line connecting said coil to an enlarged reaction drum, means for withdrawing vapors from said drum, means for superheating such vapors and means for re-injecting them into said drum, means for passing other vapors from said drum to a dephlegmator, means for condensing the dephlegmated vapors and for collecting the resulting distillate, and means for maintaining a superatmospheric pressure on the oil undergoing conversion.

3. A process for cracking oil, consisting in heating a stream of oil to a cracking temperature, in introducing the oil to an enlarged reaction zone where vaporization occurs, in augmenting the conversion of the oil in said zone by withdrawing a portion of the vapors from said zone, in superheating such withdrawn vapors and returning them to the reaction zone, and in maintaining a superatmospheric pressure on the oil undergoing treatment.

4. A process for converting oil, consisting in passing a stream of oil through a furnace where said oil is heated to a cracking temperature, in transferring the heated oil to an enlarged reaction zone where vaporization occurs, in passing evolved vapors to a dephlegmator, in withdrawing a portion of the hot vapors from the enlarged reaction zone, in superheating such withdrawn vapors and returning them to the reaction zone, and in maintaining a superatmospheric pressure on the oil stream while being heated and in said enlarged reaction zone.

5. A process for cracking hydrocarbon oil, consisting in passing a stream of oil through a passageway where said oil is heated, in transferring the heated oil to an enlarged reaction zone where vaporization occurs, in withdrawing a portion of the hot vapors from such zone, in superheating such vapors, and in returning the superheated vapors to the reaction zone to percolate through an oil body therein, and in maintaining a superatmospheric pressure on the oil undergoing conversion.

6. A process for cracking hydrocarbon oil, consisting in passing a stream of oil through a passageway where said oil is heated, in transferring the heated oil to an enlarged reaction zone where vaporization occurs, in withdrawing a portion of the hot vapors from such zone, in superheating such vapors, in returning the superheated vapors to the reaction zone to percolate through an oil

body therein, in maintaining a superatmospheric pressure on the oil undergoing conversion, and in subjecting the superheated vapors to a carbon removing treatment prior to their return to the reaction zone.

5 7. A process of cracking oil, consisting in heating a stream of oil to a cracking temperature, in transferring the heated oil to an enlarged reaction zone where vaporization occurs, in withdrawing a portion of the heated vapors from the reaction zone, and in superheating such withdrawn vapors and then returning the same to the reaction zone to commingle with the hydrocarbon products 10 therein.

15 8. A process for converting high boiling point hydrocarbon oil into products within the boiling range of motor fuels comprising subjecting the oil in liquid phase to a temperature within the cracking range, permitting separation of vapors from the unvaporized oil, subjecting portions of the vapors heavier than gasoline thus separated to vapor phase cracking at temperatures in excess of 20 1000° F., thereafter contacting the vapors with liquid oil undergoing treatment in the process at a lower temperature to extract heat from the vapors, and additionally cooling the vapors sufficiently to separate therefrom 25 all constituents heavier than the desired product by passing controlled quantities of a cooling medium through the path of travel of said vapors and returning the constituents heavier than the desired product thus obtained to the oil being heated in the liquid phase.

30 9. A process for converting high boiling point hydrocarbon oil into products within the boiling range of motor fuels comprising subjecting the oil in liquid phase to a temperature within the cracking range, separating vapors from the unvaporized oil, subjecting vapors heavier than gasoline equal to substantially 20% by weight of the oil 35 treated so obtained to vapor phase cracking at temperatures in excess of 1000° F., thence contacting the vapors with liquid hydrocarbon oil undergoing treatment in the process at a lower temperature, thence subjecting the 40 vapors to fractionation in a fractionating column, collecting in said fractionating column charging oil for the process unvaporized by contact with the vapors and constituents condensed from the vapors in said fractionating 45 column, controlling the cooling effect in said fractionating column to permit only vapors condensable into a product of the desired end point to escape therefrom, and returning the 50 collected unvaporized charging oil and condensate from said fractionating column under a mechanically applied pressure to the oil being heated in the liquid phase.

55 10. A process for converting high boiling point hydrocarbons into products within the boiling range of motor fuels comprising

subjecting the heavy hydrocarbons to a liquid phase heat treatment in a heating coil at a temperature within the cracking range but not substantially above 750° F. to effect liberation of substantial quantities of vapors 70 therefrom, subjecting a portion of the vapors heavier than gasoline liberated from the oil to vapor phase cracking at a temperature of substantially 1100° F., thereafter immediately passing such vapors in physical contact with liquid hydrocarbons at a lower temperature, thence subjecting the vapors to fractionation to condensate therefrom all constituents boiling above the end point of the desired product, controlling said fractionation by flowing regulated quantities of a cooling medium through the path of travel of the vapors undergoing fractionation, utilizing charging oil for the process to assist in the cooling of the vapors, collecting unvaporized portions of the charging oil thus utilized and condensate separated from the vapors during fractionation and passing the thus collected condensate and unvaporized charging oil under a mechanically applied pressure to the liquid phase heating coil.

80 11. A process for converting relatively high boiling point hydrocarbon oils into lower boiling point products within the boiling range of motor fuels comprising passing the relatively heavy hydrocarbon oil through a liquid phase heating coil wherein it is heated to a temperature within the cracking range but not substantially above 750° F., 85 separating vapors from the oil thus heated, passing condensable vapors equal to 20% by weight of the oil treated thus derived through additional heating elements wherein they are subjected to vapor phase cracking at a temperature of approximately 1100° F., thence contacting the vapors with liquid hydrocarbon oil at a lower temperature, delivering vapors subsequent to contact with the liquid hydrocarbon oil at a lower temperature to a fractionating column, facilitating said fractionation in said fractionating column by passing therethrough a cooling medium, collecting at the base of said fractionating column a quantity of condensate separated from the vapors in the fractionating column and unvaporized portions of charging oil for the process which has been utilized as a cooling medium for the vapors, and forcing the collected unvaporized charging oil and condensate from the base of said fractionating column under mechanically applied pressure through said liquid phase heating coil.

90 12. A process for cracking hydrocarbon oils in which the oil constituents treated are subjected to a primary and a secondary heat treatment at relatively lower and higher cracking temperatures in different stages of the process, comprising subjecting the charging oil to the primary heat treatment by 100 110 115 120 125 130

heating the same in liquid phase to said relatively lower cracking temperature, introducing the charging oil thus heated to an enlarged zone wherein vaporization of 5 lighter products from heavy unvaporized oil occurs, removing one portion of the products vaporized from the unvaporized oil in said enlarged zone, passing said removed portion through a heating element wherein said portion is subjected to said secondary heat treatment to effect substantial vapor phase cracking at temperatures of the order of 1000° F. or above, reintroducing the vaporous products subjected to said secondary heat treatment into said enlarged zone to physically commingle with the heated charging oil, being admitted thereto from said primary heat treatment, to effect heat exchange between said portion and said charging oil to cool 10 said portion, and facilitating distillation of 20 said charging oil, removing heavy unvaporized oil from said enlarged zone without returning the same to either of said heat treatments, and taking off additional portions of 25 the vapors separated from the heavy oil in said enlarged zone for subsequent condensation.

13. A process for cracking hydrocarbon oils in which the oil constituents treated are 30 subjected to a primary and a secondary heat treatment at relatively lower and higher cracking temperatures in different stages of the process, comprising subjecting the charging oil to the primary heat treatment by 35 heating the same in liquid phase to said relatively lower temperature, introducing the charging oil thus heated to an enlarged zone wherein vaporization of lighter products from heavy unvaporized oil occurs, re- 40 moving one portion of the products vaporized from the unvaporized oil in said enlarged zone, passing said removed portion of the vapors through a heating element wherein said portion of the vapors is sub- 45 jected to said secondary heat treatment to effect substantial vapor phase cracking at temperatures of the order of 1000° F. or above, reintroducing the products subjected to said secondary heat treatment into said en- 50 larged zone to physically commingle with the heated charging oil being admitted thereto from said primary heat treatment, to effect heat exchange between said portion of the vapors and said charging oil to cool said 55 portion, and facilitating distillation of said charging oil, removing heavy unvaporized oil from said enlarged zone without returning the same to either of said heat treatments, taking off additional portions of the vapors 60 separated from the heavy oil in said enlarged zone for subsequent condensation, and facilitating the cooling of said additional portion of the vapors by causing the same to flow in heat interchange relation with final distillate 65 produced in the process.

14. An apparatus for cracking hydrocarbon oil comprising an enlarged chamber, a primary and a secondary heating means, means for passing charging oil for the process through said primary heating means, means 70 for delivering charging oil from said primary heating means to said enlarged chamber, means for removing heavy unvaporized oil from said enlarged chamber without returning same to either of said heating means, 75 means for separately removing from said enlarged chamber different portions of the lighter products separated in vaporous form from the heavy oil in said enlarged chamber, means for passing one portion of the products vaporized in said chamber through said secondary heating means, means for elevating said portion in vaporous form to a tem- 80 perature above 1000° F. in said secondary heating means, means for reintroducing the vapor heated in said secondary heating means into said enlarged chamber into physical contact with the oil delivered thereto from said primary heating means, and means for subjecting the portion of 85 vapors separately removed from said enlarged chamber to cooling to effect condensation thereof.

15. An apparatus for cracking hydrocarbon oil comprising an enlarged chamber, a primary and a secondary heating means, means for passing charging oil for the process through said primary heating means, means for delivery charging oil from said primary heating means to said enlarged chamber, means for removing heavy unvaporized oil from said enlarged chamber without returning same to either of said heating means, 90 means for separately removing from said enlarged chamber different portions of the lighter products vaporized from the heavy oil in said enlarged chamber, means for passing one portion of the lighter products thus removed through said secondary heating means, means for elevating said portion of the lighter products to a temperature, 95 above 1000° F. in said secondary heating means, means for reintroducing the portion of the light products heated in said secondary heating means into said enlarged chamber 100 into physical contact with the oil delivered thereto from said primary heating means, means for subjecting the portion of the lighter products separately removed from said enlarged chamber to cooling to effect condensation thereof, means for collecting the final distillate, and means for returning portions thereof to act as a cooling medium for 105 the vapors.

16. An apparatus for cracking hydrocarbon oil comprising an enlarged chamber, a primary and a secondary heating means, means for passing charging oil for the process through said primary heating means, means for delivering charging oil from said 115 120 125 130 135

primary heating means to said enlarged chamber, means for removing heavy unvaporized oil from said enlarged chamber without returning same to either of said heating means, means for separately removing from said enlarged chamber different portions of the lighter products vaporized from the heavy oil in said enlarged chamber, means including a pump for passing one portion of the previously vaporized products thus removed through said secondary heating means, means for elevating said portion to a temperature above 1000° F. in said secondary heating means, means for reintroducing the vaporized products heated in said secondary heating means into said enlarged chamber into physical contact with the oil delivered thereto from said primary heating means, means for subjecting the portion of the lighter vaporized products separately removed from said enlarged chamber to cooling to effect condensation thereof, means for collecting the final distillate, and means including a pump, for returning portions thereof to act as a cooling medium for the vapors.

17. A process for cracking hydrocarbon oils in which the oil constituents treated attain relatively higher and lower cracking temperatures in different stages of the process comprising subjecting the charging oil in one stage of the process to temperature conditions adequate to cause the charging oil to attain said relatively lower cracking temperature while substantially in liquid phase, collecting a body of the charging oil in a reaction and vaporizing zone, taking off a part of the constituents vaporized in said reaction and vaporizing zone subjecting said part of the constituents to vapor phase cracking at temperatures of 1000° F. or above, reintroducing the vapors so subjected to vapor phase cracking into said reaction and vaporizing zone to commingle with the unvaporized oil therein and impart heat thereto to facilitate conversion and distillation of the charging oil in the reaction and vaporizing zone, removing residual oil from said reaction zone without further heat treatment in the process, separately taking off from said reaction and vaporizing zone a second part of the constituents vaporized therein and subjecting said second part of said constituents to condensation.

55 JEAN DELATTRE-SEGUY.
